MECHANICAL MOVEMENT AND ELECTRIC-LIGHT SOCKET.

1,046,410.

Specification of Letters Patent.

Patented Dec. 3, 1912.

Original application filed December 30, 1911, Serial No. 668,632. Divided and this application filed March 29, 1912. Serial No. 687,183.

To all whom it may concern:

Be it known that I, TONJES AUGUST CARL BOTH, a citizen of the United States, and a resident of Malden, in the county of Middlesex and State of Massachusetts, have invented certain new and useful Improvements in Mechanical Movements and Electric-Light Sockets, of which the following is a specification, taken in connection with the accompanying drawing, which forms a part of the same, this application being a division of my copending application, Serial No. 668,632.

My invention relates to mechanical movements adapted for universal application. Further to electric light sockets and to certain details of construction of both the mechanical movement and the electric light socket, which will be more fully hereinafter described in the specification and pointed out in the claims.

I have shown my mechanical movement as a switch mechanism in an electric light socket, to which it is particularly adapted owing to its simplicity, the few parts, and the small space occupied by them. When so used it makes a quick make and a quick break of the electric current, without arcing, upon the operation of the driving member in either direction.

Among other advantages my mechanical movement permits the socket to be formed smaller and stronger for the opening in which the mechanical movement is mounted need not be so large as for other switch mechanism. In illustrating my invention I have, therefore, by way of example, shown it as a switch mechanism in an electric light socket, but it is to be understood, of course, that the mechanical movement is not to be limited to this use.

In the accompanying drawing showing illustrative embodiments of my invention and in which the same reference numerals refer to similar parts in the several figures,—Figure 1 is a longitudinal vertical section through my electric light socket, one of the insulating members being shown in side elevation; Fig. 2 is a longitudinal vertical section through my electric light socket, substantially at right angles to the section shown in Fig. 1; Fig. 3 is a side elevation of the screw shell; Fig. 4 is a plan view of the

screw shell; Fig. 5 is a perspective view of one form of resilient driven member, the parts being shown disconnected; Fig. 6 is a perspective view of the preferred form of driving member; Fig. 7 is a plan view of a blank from which one form of driven member may be formed; Fig. 8 is a side elevation of the driven member formed by bending the blank illustrated in Fig. 7; Fig. 9 is a horizontal section substantially on the line 9—9 of Fig. 2; Fig. 10 is a fragmentary sectional view showing a detail.

In the illustrative embodiments of my invention shown in the drawing, 1 is an electric light socket formed of two complementary insulating members 2 and 3 having meeting surfaces 4, 4, Fig. 2, which coincide substantially with the longitudinal axis of the electric light socket, though portions of the meeting surfaces are preferably offset as at 5, Fig. 2. These insulating members 2 and 3 are preferably formed from porcelain and without cross holes and each of them is provided with a recess 6 which together form an interior recess or chamber 7 for the reception of my mechanical movement when it is used as a switch mechanism in this form of electric light socket. Each of the recesses 6, 6 has an offset or deeper recess 8, Fig. 2, which form guides for the offset portions 9, 9, Fig. 5, or 10, 10, Fig. 7, of the respective resilient driven members 11 and 12. I also form in the cooperating faces of each of the insulating members 2 and 3, two semi-circular openings 13, 14 to receive the respective cams 15 and 16 carried by the driving member 17. The holes or recesses 18, 18, Fig. 2 are also molded in the insulating members 2 and 3 for the reception of the bearings 19, 19 of the intermediate or movable hill and valley member 20. I attach the insulating members 2 and 3 to a lamp holding member which is usually, though not necessarily, in the form of a screw shell 21. The upper portion of the screw shell 21 is provided with a lip 22; Figs. 1, 3 and 4 which extends up into the interior chamber 7 and forms one contact. I also preferably provide the head of this screw shell 21 with a dovetail 23 to cooperate with the dovetails 24, 24 formed in the respective insulating members 2 and 3. I also preferably provide each of the insulating

members 2 and 3 with another dovetail 25, Fig. 1, which takes under the head 26 of the screw shell 21. In this form of my invention the intermediate or movable hill and 5 valley member 20 is formed of some insulating material and provided at each end with a "valley" 28, each "valley" having a ledge or shoulder 29 and a boot, kicker or accelerator 30. The "hill" 31 is that portion of the intermediate member 20 which connects the two valleys 28, 28.

My preferred form of resilient driven member, in this invention, is one formed from a plurality of stampings 131 and 32, 10 Figs. 1 and 5, having coöperating engaging surfaces 33, 34 to be connected together forming the resilient driven member 11, Fig. 5. I form these engaging surfaces 33 and 34 as a hook on one member and a slot 15 on the other, the particular form of engaging surfaces shown, however, are merely by way of example. The stamping 131 which I will refer to as a shoe, is preferably, though not necessarily provided with the offsets 9, 9. The upper stamping 32 is provided with an engaging surface 35 to coöperate with the movable intermediate or hill and valley member 20. On assembling the shoe 131 and the member 32, a very 20 strong resilient member 11 is formed.

Instead of using a resilient member formed of a plurality of parts, I may in some cases use a resilient member formed out of one piece of material. I have shown 25 such a resilient member in Figs. 7 and 8. In this form, the blank 36, Fig. 7, is preferably provided with the offsets 10, 10 and also with one or more ribs 37, 37 which serve to strengthen the resilient member 12 when 30 the blank is bent back on itself, Fig. 8. In this form, the surface 38 coöperates with the intermediate hill and valley member 20.

I have found that it is quite desirable to insulate the key or driving member 17 from 35 the switch mechanism so that a metal key or a key formed of other conducting material 40 may be placed upon the end 39 of the driving member. It is often quite desirable to have the metallic key harmonize 45 with the metal of the casing or the cluster or other installation with which it is used. With such a device a key may be placed upon the end 39 of the driving member which would be of the same material and 50 ornamented in the same way, if desired, as the metallic casing or installation, or some other metal may be used to make the key 40 blend with any particular color scheme.

My intermediate or hill and valley member 20 is preferably formed of porcelain and rocks upon the pivot 19 received in the recesses 18, 18 in the respective insulating members 2 and 3.

My driving member 17 is preferably 55 formed of wire and bent to form the cams

15 and 16. It is supported in any suitable manner as by a bearing 55 mounted in slots 56, 56 in the insulating members 2 and 3, Figs. 1 and 10.

Upon the rotation of the key or driving 70 shaft 17 in either direction, the cam 15 or 16, as the case may be, will coöperate with the insulating intermediate or hill and valley member 20 and cause the resilient driven member 11 or 12, whichever one is used, 75 to store up energy by causing the two free ends of the resilient driven member to approach each other. When sufficient energy has been stored up in the spring or driven member 11 or 12, the kicker or accelerator 80 30, at a certain predetermined position on the rocking of the intermediate member 20, will crowd the end 35 of the driven member 11 or the end 38 of the driven member 12 out of the valley 28 with which it has 85 been in engagement and over its adjacent ledge 29. This will then cause the entire resilient driven member, whichever form is used, to fly over with a positive snap from the position shown in Fig. 1 and at the same 90 time, the consuming device, whatever it may be, will be thrown into circuit by the end 42 of the driven member 11, or the end 43 of the driven member 12, whichever form is used, contacting with the arm 44 of the binding post 45 and with the lip 22 of the screw shell 21, the current passing through the resilient driven member 11 or 12 as the case may be. To disconnect the consuming device, it is merely necessary to rotate the 100 driving member 17 or key shaft, in either direction, when power will be again stored up in the resilient driven member until such time as the intermediate or movable hill and valley member 20 has reached substantially the position shown in Fig. 1, when the resilient driven member will, with a quick and positive snap, fly over to the position in which it is shown in Fig. 1, when the current will be disconnected instantaneously 105 and without arcing. It will be further noted that the intermediate member 20, in my present invention, serves as a part of the mechanical movement and in addition as an 110 insulating member to insulate a portion of the mechanical movement from another portion. In the form shown, by way of example, the insulating intermediate member 20 serves to insulate the key shaft or driving member 17 from the driven member 11 115 or 120 whichever is used.

I provide my socket with a center contact 46, carried by the binding post 47. Preferably, though not necessarily, the two are formed out of one piece of material. The center contact is positioned within the shell 21 in any suitable manner as by passing it through the opening 27 in the shell. The binding post 47 is secured in any suitable manner to the insulating base, prefer- 125 130

ably by means of the screw 48. The binding post 47 is provided with the binding screw 49. The other binding post 45 is provided with a similar binding screw 50. The binding post 45 is secured to the insulating base by the screw 51 which also serves to hold the two insulating members 2 and 3 together.

To guide the resilient member 11 or 12, I preferably bring the walls 52, 52 of the recesses 6, 6 up adjacent to the spring member. The offsets 9, 9 or 10, 10 are received in the enlarged or deeper recesses 8, 8, the shoulders 53, 53 serve as an additional pre- caution and act as stops to prevent the driven member 11 or 12, as the case may be from snapping over too far to the right of Fig. 1. Ordinarily this movement will be limited by the end 35 or 38 contacting with the elevated valley 28 of the intermediate member 20. Should there, however, be any tendency to an excessive lateral movement, the shoulders or stops 53, 53, Fig. 9, will prevent it.

While my invention is adapted and is preferably to be used with a socket shell and a socket cap to surround my electric light socket, the shell and cap form no part of my present invention and are omitted. Such a surrounding shell and cap are well known in the art. A cap and shell are illustrated in my companion application Ser. No. 668,632 of which this is a division.

Having thus described this invention in connection with the several illustrative embodiments thereof to the details of which I do not desire to be limited, what is claimed as new and what it is desired to secure by Letters Patent is set forth in the appended claims.

I claim—

1. In a mechanical movement, the combination of a rotary driving member provided with surfaces to operate an insulating member, a movable insulating member mounted independently of the rotary driving member and adapted to be operated by the rotary driving member, and a resilient driven member having a portion coöperating with the said movable insulating member.

2. In a mechanical movement, the combination of a rotary driving member provided with surfaces to operate an insulating member, a pivoted insulating member mounted independently of the rotary driving member and adapted to be operated by the rotary driving member, and a resilient driven member having a portion coöperating with said movable insulating member.

3. In a mechanical movement, the combination of a driving member provided with operating surfaces to coöperate with the insulating member, a resilient driven member, and a separate insulating member provided

its ends to receive and coöperate with a portion of the resilient member.

4. In a mechanical movement, the combination of a driving member provided with operating surfaces to coöperate with the insulating member, a resilient driven member, and a separate insulating member provided with holding grooves or valleys and accelerators or kickers at each of its ends to receive and coöperate with a portion of the resilient member.

5. In electric switch mechanism, the combination of a driving shaft of wire bent to form substantially closed opposed loops to form opposed cams and contact mechanism operated by the driving shaft.

6. An article of manufacture for a mechanical movement comprising a resilient driven member formed of a plurality of parts, each part having near one end co-operating locking surfaces, the other end of the parts being separated and adapted to move toward and from each other.

7. An article of manufacture for a mechanical movement comprising two spring members provided near one of the ends with interlocking coöperating surfaces, the other ends of the spring members being separated and free to move to and from each other, one of the spring members being provided with offset portions.

8. In electric light sockets, the combination of a switch mechanism including a driving member and a pivoted insulating member, said insulating member being located between the driving member and the other portions of the switch mechanism to insulate the driving member and adapted to move independently of the driving member.

9. In electric switch mechanism, the combination of a conducting driving member, a sliding conducting driven member, and insulating means between the driving and driven sliding conducting members adapted to transmit power from the conducting driving member to the sliding conducting driven member.

10. In electric switch mechanism, the combination of a conducting rotary driving member, a sliding conducting driven member, and insulating means between the rotary driving and sliding driven conducting members adapted to transmit power from the conducting rotary driving member to the sliding conducting driven member.

11. In electric switch mechanism, the combination of a conducting driving member, a conducting bodily reciprocating driven member, and rocking insulating means between the driving and reciprocating driven conducting members adapted to transmit power from the conducting driving member to the conducting reciprocating driven member.

12. In electric switch mechanism, the com-

bination of a conducting rotary driving member, a conducting sliding driven member, and rocking insulating means between the driving and driven conducting members 5 adapted to transmit power from the conducting driving member to the conducting driven member.

13. In electric switch mechanism, the combination of a conducting driving member, a 10 resilient bodily reciprocating conducting driven member, and independently movable insulating means between the driving and driven conducting members adapted to put the bodily reciprocating resilient conducting 15 member under tension upon the operation of the conducting driving member.

14. In electric switch mechanism, the combination of a rotary conducting driving member, a sliding resilient conducting 20 driven member, and insulating means between the rotary driving and driven conducting members adapted to put the resilient conducting member under tension upon the rotation of the conducting driving member.

25 15. In electric switch mechanism, the combination of a rotary conducting driving member, a reciprocating resilient conducting driven member, and insulating means 30 between the rotary driving and reciprocating driven conducting members mounted independently of the driving and driven members and adapted to have relative movement with relation to them and provided 35 with means adapted to put the reciprocating resilient conducting member under tension upon the rotation of the conducting driving member.

40 16. In electric switch mechanism, the combination of a conducting driving member, a resilient conducting driven member, and insulating means between the driving and driven conducting members mounted independently of the driving and driven members and adapted to have relative movement 45 with relation to them and provided with means adapted upon the rotation, in either direction, of the conducting driving member to put the reciprocating resilient conducting 50 member under tension.

55 17. In electric light sockets, the combination of an insulating base, a metallic key shaft, a metallic resilient driven member to directly make and break the electric connection, and a movable insulating member between the key shaft and the metallic resilient driven member mounted independently of the key shaft and the resilient driven member and provided with means adapted 60 to put the resilient driven member under tension.

18. In electric light sockets, the combina-

tion of an insulating base, a metallic key shaft adapted to rotate in either direction, a metallic resilient driven member to directly make and break the electric connection and a movable insulating member between the key shaft and the metallic resilient driven member mounted independently of the key shaft and the resilient driven member and provided with means adapted to put the resilient driven member under tension.

19. In electric light sockets, the combination of an insulating base, a metallic key shaft, a metallic resilient bodily movable 75 driven member to directly make and break the electric connection and a pivoted insulating member between the key shaft and the bodily movable metallic resilient driven member and adapted both to transmit power 80 from the key shaft and to insulate it from the other parts of the switch mechanism.

20. In electric light sockets, the combination of an insulating base, a metallic key shaft adapted to rotate in either direction, a metallic resilient driven member to directly make and break the electric connection, and a pivoted insulating member between the key shaft and the metallic resilient driven member and adapted both to transmit power 85 from the key shaft upon rotation in either direction, and to insulate it from the other parts of the switch mechanism.

21. In electric light sockets, the combination of an insulating base, a metallic key shaft provided with opposed cams, a resilient reciprocating metallic contact member, and insulating means coöperating with the cams and with the reciprocating metallic contact member and insulating the key shaft 95 from the other portion of the switch mechanism.

22. In electric light sockets, the combination of an insulating base, a wire key shaft 105 bent to form opposed cams, a resilient reciprocating metallic contact member, and insulating means coöperating with the cams and with the reciprocating metallic contact member and insulating the key shaft from the other portion of the switch mechanism.

23. In electric light sockets, the combination of an insulating base, a metallic key shaft provided with opposed cams, a resilient reciprocating metallic contact member, and pivoted insulating means coöperating 115 with the cams and with the reciprocating metallic contact member and insulating the key shaft from the other portion of the switch mechanism.

TONJES AUGUST CARL BOTH.
